UNITED STATES PATENT OFFICE.

FREDERICK WILHELM ROETTGES, OF BROOKLYN, NEW YORK.

DESIGN FOR A COMBINED LAMP SHADE AND STAND OR AN ARTICLE OF SIMILAR NATURE.

Application filed April 15, 1924. Serial No. 9,289. Term of patent 3½ years.

To all whom it may concern:

Be it known that I, FREDERICK WILHELM ROETTGES, a citizen of Germany, having declared my intention of becoming a citizen of the United States, residing at Brooklyn, in the county of Kings and State of New York, have invented a new, original, and ornamental Design for a Combined Lamp Shade and Stand or an Article of Similar Nature, of which the following is a specification, reference being had to the accompanying drawing, forming a part thereof.

The figure is a perspective view of a combined lamp shade and stand showing my new design.

I claim:

The ornamental design for a combined lamp shade and stand, or an article of similar nature as shown.

In testimony whereof, I affix my signature.

FREDERICK WILHELM ROETTGES.
